5 Claims. (Cl. 313—250)

This invention relates to modular devices for electronics. More particularly, the invention relates to modular, space-discharge tubes.

In the construction of modular packaging for electronic components as described in National Bureau of Standards Technical News Bulletin Number 11, volume 37, November 1953, it has been a problem to provide compatible space-discharge tubes. As described and illustrated in NBS Bulletin Number 11, such modules are typically formed of a plurality of congruently stacked, spaced, ceramic wafers having perimetrically disposed indentations formed therein. The wafers have metallic conductive paths affixed thereto and are supported in place by riser wires or conductors disposed in the wafer indentations. The indentations are coated with silver which is caused to adhere to the riser wires as, for example, by soldering or brazing.

In the prior art space-discharge tubes, particularly electron-discharge tubes, are formed primarily from glass envelopes and metal or phenolic bases. The electrodes typically are vertically supported by metallic conductors which extend from the base of the tube. Such tubes do not operate satisfactorily at temperatures in excess of 185° C. Furthermore, these tubes are extremely susceptible to mechanical shock and vibration. Additionally, these tubes are not readily integrated into modular units.

In the structure of modular, ceramic, space-discharge tubes as described and illustrated in a copending application entitled "Modular Electron-Discharge Tube," filed April 16, 1956, Serial No. 578,385, now abandoned, by Christopher Karabats and James D. LeVan, it has been a problem to reduce the inter-electrode capacity. This problem arises because of the high dielectric constant of ceramic materials coupled with the presence of metallic conductive paths on opposite sides of a given ceramic wafer which connect different electrodes. The particular inter-electrode capacities producing considerable difficulty are the control-grid-to-cathode and control-grid-to-plate capacities.

It is, therefore, an object of the invention to provide an improved modular, space-discharge tube operable at temperatures in excess of 600° C.

A further object of the invention is to provide an improved modular, space-discharge tube capable of withstanding a high degree of mechanical shock and vibration.

A still further object of the invention is to provide an improved modular, electron-discharge tube having reduced inter-electrode capacity.

In accordance with the invention there is provided a modular, space-discharge tube. The tube comprises a pair of end wafers and a plurality of inner wafers stacked between end wafers. The inner wafers have holes centrally formed therein. A plurality of staggered conductive paths are affixed to opposite sides of the inner wafers. One of the paths extends into the central hole in one of the wafers. An electrode is secured longitudinally to the inside surface of the central hole in one of the wafers to confine contact of the extended path and the inside surface

to present a minimum of conductive surface area to an adjacent electrode and thereby, minimize inter-electrode capacity.

For a better understanding of the present invention, together with other and further objects thereof, reference is made to the following description taken in connection with the accompanying drawing and its scope will be pointed out in the appended claims.

In the drawings:

10 Fig. 1 is a perspective view of an electron-discharge tube embodying the invention;

Fig. 2 is a perspective view, in exploded form and partially in section, of an electron-discharge tube embodying the invention; and

15 Fig. 3 is a sectional view of the embodiment in Fig. 1.

Description of the discharge tube in Figs. 1-3

Referring now to the drawings, there is here illustrated a modular, space-discharge tube. While the embodiment illustrated and described herein is particularly directed to an electron-discharge tube, the term "space-discharge tube" is employed to include both vacuum and gas discharge tubes in which either negative or positively charged particles are transmitted through space. The electron-discharge tube here illustrated is a twin-triode having a heater 13, a pair of cathodes 14, a pair of control grids 17, and a pair of anodes 16 contained within and supported by a plurality of congruently stacked, ceramic wafers. Thus, in detail, and referring particularly to Fig. 2, the tube comprises a plurality of congruently stacked, ceramic wafers 10a—10h, each having a metallic conductive path 11 affixed thereto. The inner wafers 10b—10g, inclusive, have circular holes 12 centrally formed therein. The end wafers 10a and 10h enclose the ends of the tube and seal the discharge space formed by the holes 12. The heater element 13, disposed at approximately midpoint axially and diametrically of the holes 12, is secured between the middle pair of adjacent wafers 10d and 10e. The cathodes 14, in the form of a pair of disks, are individually secured between different ones of the pairs of wafers 10c, 10d and 10e, 10f.

45 The control grid electrodes 17 have an annular ferrule member 17a affixed to a grid disk 17b. The ferrule members are secured in the central holes respectively of the wafers 10c and 10f, with each of the grid disks 17b facing its adjacent cathode 14. The diameter of the ferrule members 17a is so chosen as to require a press fit between the ferrule members and the inside surface of the central holes 12. Conductors 11a affixed to wafers 10c and 10f each extend from a peripheral indentation 15 into the holes 12 as shown. The ferrules 17a contact the conductors 11a to effect an electrical connection therebetween. The ferrules 17a are secured to the inside surface of the holes 12 by means of well-known ceramic-to-metal seals.

50 The anodes 16 are disposed between end wafers and the adjacent inner wafers, one between the wafers 10a and 10b and the other between the wafers 10g and 10h. The electrodes other than the grids 17 are flanged to enable peripheral securing between pairs of wafers in contact with a conductive path 11 on each of these wafers to provide means for making external connections to the electrodes and are shaped, as shown, to provide a suitable spacing between electrodes.

65 The wafers have perimetrically disposed indentations 15 to provide means for external connections. The conductive paths 11 are terminated in and connected to selected indentations 15 for effecting a desired matrix of connections. The indentations 15 are preferably silver-coated and solder-filled and a plurality of riser wires 18 are disposed therein and, for example, soldered or welded in place. The tube is assembled by effecting ceramic-to-

metal seals between the wafers and the electrodes and ceramic-to-ceramic seals between the wafers. Such ceramic-to-metal seals are well known; for example, see "Materials Technology for Electron Tubes" by Walter H. Kohl, published by Reinhold Publishing Corporation, 1951, chapter 16, pages 403-421. The tube being of modular form may also be mounted as an extended portion of a module with common riser connections being made to the module and the modular tube.

In prior art modular, ceramic tubes, it has been found that inter-electrode capacitances, for example, the control-grid-to-cathode and control-grid-to-anode capacitances, are in the order of 12 micromicrofarads. The effect of such a high inter-electrode capacitance is to severely limit the performance of the tube at high frequencies. It will be apparent that the structure of the control grids 17 may be reproduced for the other electrodes to obtain the minimum overall inter-electrode capacity. Merely by utilizing the structure of the control grids 17 as disclosed herein produces a decrease in grid-to-cathode and grid-to-anode capacitance from 12 micromicrofarads to less than 2 micromicrofarads.

One form of the ceramic tube embodying the present invention is .875" square and .28" in height. The volume of a twin-triode tube embodying the present invention can be less than .12 cubic inch as compared with 6 cubic inches for standard receiving tubes. Such a tube, however, is capable of operating at temperatures in excess of 600° C. as compared with the conventional limitation to 185° C. Furthermore, tubes embodying the present invention are capable of dissipating in excess of 8 watts of power as compared with conventional tubes which are limited to 1 watt.

While applicant does not intend to be limited to any particular shapes, sizes or materials of parts in the embodiment of the invention just described, there follows a set of dimensions and materials for the more important parts which have been found to be particularly suitable for a twin-triode amplifier tube of the type represented in Figs. 1 and 2:

Heater 13—.75" long by .026" in diameter, formed from .002" tungsten wire with .002" aluminum oxide insulation;

Cathodes 14—outer diameter of flange .350"; outer diameter of disk .280"; material—nickel base with a coating of .002" barium strontium;

Wafer holes 12—.340" in diameter;

Control grids 17—ferrule 17a—outer diameter .345"; diameter of grid disk 17b .240"; height .035"; material—grid mesh .001" thick nickel; ferrule .002" thick nickel;

Anodes 16—flange outer diameter .410"; flange inner diameter .330"; outer diameter of anode disk .280"; height .055"; material—nickel .005" thick;

Spacing between end wafers and anodes 16—.053";

Anodes 16 to control grids 17 spacing—.018";

Control grid 17 to cathode 14 spacing—.005"; and

Total thickness of the two cathodes 14 and heater 13 structure—.040".

It will be apparent from the above description that while the structure presented by the present invention has more immediate application to electron-discharge tubes, it is suitable for all modular, space-discharge tubes. It will be further apparent from the above description that the discharge tube of the invention fulfills a critical need in an area where other modern devices such as transistors, amplifiers, capacitive amplifiers and conventional discharge tubes are unsuitable.

While there has been described what is at present considered to be the preferred embodiment of this invention, it will be obvious to those skilled in the art that various changes and modifications may be made therein without departing from the invention, and it is, therefore, aimed in the appended claims to cover all such

changes and modifications as fall within the true spirit and scope of the invention.

What is claimed is:

- 5 1. A modular, space-discharge tube, comprising: a pair of end wafers; a plurality of inner wafers stacked with said end wafers and having holes centrally formed therein; a plurality of staggered conductive paths affixed to opposite sides of said inner wafers, one of said paths extending into the central hole in one of said wafers; and an electrode secured longitudinally to the inside surface of said central hole in one of said wafers to confine contact of said extended path and said inside surface to present a minimum of conductive surface area to an adjacent electrode and, thereby, minimize inter-electrode capacity.
- 10 2. A modular, space-discharge tube, comprising: a pair of end wafers; a plurality of inner wafers stacked with said end wafers and having holes centrally formed therein; a plurality of staggered conductive paths affixed to opposite sides of said inner wafers, one of said paths extending into the central holes in one each of two said wafers; and a control grid electrode having an annular ferrule member secured longitudinally to the inside surface of said central hole in one of said wafers to confine contact to said extended path and said inside surface to present a minimum conductive surface area to an adjacent electrode and, thereby, minimize inter-electrode capacity.
- 15 3. A modular, ceramic, electron-discharge tube, comprising: a pair of end ceramic wafers having perimetricaly disposed indentations formed therein; a plurality of inner, ceramic wafers with perimetricaly disposed indentations and stacked congruently with said end wafers, said inner wafers having holes centrally therein; a plurality of staggered conductive paths affixed to opposite sides of said inner wafers, a pair of said paths each extending into the central hole in one each of two said wafers; a heater element secured between a pair of adjacent inner wafers and disposed in said holes; a pair of cathode disks disposed adjacent opposite sides of said heater and secured to adjacent inner wafers; a pair of control grid electrodes each having an annular ferrule member secured to the inside surface of said central hole in one each of said wafers and contacting the path extending therein; a pair of anodes each disposed between an end wafer and its adjacent inner wafer with said control grids between said anodes and cathodes; metallic conductive paths affixed to said wafers and selectively connecting said electrodes and heater to said indentations; and a plurality of riser conductors disposed in said indentations and connected to said paths providing an integral, multi-unit, modular electron-discharge tube with external connections.
- 20 4. A modular, space-discharge tube, comprising: a pair of end wafers; an inner wafer stacked between said end wafers and having a central hole, said hole providing a discharge space; a conductive path affixed to a side of said inner wafer and extending from a wafer extremity into the inside wafer surface defining said central hole; and an electrode secured longitudinally to said inside wafer surface of said hole to confine contact to said extended path in said hole and said inside surface to present a minimum conductive surface area to an adjacent electrode and thereby minimize electrode capacity.
- 25 5. A modular, ceramic, electron-discharge tube, comprising: a pair of end ceramic wafers having perimetricaly disposed indentations; a plurality of inner, ceramic wafers with perimetricaly disposed indentations corresponding with the first said indentations and stacked between said end wafers congruently therewith, said inner wafers having central holes providing a discharge space; a conductive path affixed to the flat side of one of said inner wafers extending from one end of its indentations into the inside wafer surface of its central hole; a heater element secured between a pair of adjacent wafers and
